CONTROL PANEL FOR A LAUNDRY APPLIANCE

Anthony M. Kulusic, Chesterton, Ind., and Melvin H. Boldt, Glenview, Ill., assignors to Borg Warner Corporation, Chicago, Ill., a corporation of Illinois

Filed July 5, 1963, Ser. No. 75,680

Term of patent 14 years

(Cl. D49—1)

Fig. 1

FIG. 1 is a front perspective view for a control panel for a laundry appliance, showing our new design;

FIG. 2 is a front elevational view thereof;

FIG. 3 is a side elevational view thereof; and

FIG. 4 is a top plan view thereof.

The dominant features of the design reside in the portion shown in full lines.

We claim:

The ornamental design for a control panel for a laundry appliance, substantially as shown and described.
